UNITED STATES PATENT OFFICE

THOMAS W. PHILLIPS, OF JACKSON, MICHIGAN

GOLF TEE

Application filed August 30, 1929. Serial No. 389,333.

The main object of this invention is to provide a golf tee which may be formed of cardboard or like material, which readily disintegrates when exposed to the weather, 5 may be carried in the flat and readily set up for use and when erected is quite substantial and serves as an effective seat or support for the ball.

A further object is to provide a golf tee 10 having these advantages which may be employed for advertising purposes, presenting a substantial surface for advertising matter.

Objects pertaining to details and economies of my invention will definitely appear 15 from the description to follow. The invention is defined in the claims.

A structure which embodies the features 20 of my invention is clearly illustrated in the accompanying drawing in which:

Fig. 1 is a perspective view of one of my improved golf tees in erected position, a ball being shown thereon by dotted lines.

Fig. 2 is a vertical central section. 25 Fig. 3 is a perspective view of one of the tees in the flat or knock-down.

Fig. 4 is a fragmentary plan view of a sheet containing a plurality of the tees.

My improved golf tees are formed of 30 strips of bendable material, preferably light card board, and comprise a central portion 1 constituting the top of the tee, intermediate portions 2 constituting the sides or upright portions of the tee, and end portions 3 and 4 constituting the base or bottom portions of the tee. The strip has transverse scoring lines 5 between these portions to facilitate folding.

The end portion 3 has a transverse slot 6 35 therein while the end portion 4 has longitudinal slots 7 extending from its end providing a tongue 8 adapted to be inserted through the slot 6 as shown in Fig. 2, thereby by interlocking the base portions and securely retaining the device in erected position with the side portions in downwardly diverging relation as shown in Fig. 2.

It will be readily understood that by telescoping the bottom portions more or less

the height of the tee can be considerably varied.

The top portion is provided with a central hole 9 providing a seat for the ball as indicated at 10 in Fig. 1. This seat opening is of substantial dimensions so that the ball will remain on the tee, even though the top is not exactly horizontal. 55

In practice I preferably form the tee strips of a sheet of material as shown in Fig. 60 4, the several tee strips being separated by the scoring lines 11 so that the tees may be removed from the sheet as desired. By forming in this manner the tees may be very economically produced and are convenient to carry. 65

The tees are well adapted to receive advertising matter and may be produced cheaply enough so that they can be employed purely as an advertising medium, if 70 desired.

Having thus described my invention what I claim as new and desire to secure by Letters Patent is:

1. A golf tee comprising a strip of bendable material having transverse scores facilitating folding along predetermined lines and comprising a top portion having a hole therein adapted to provide a ball seat, side portions at each side thereof, and base portions, one of said base portions being provided with a transverse slot and the other being longitudinally slotted from its end to provide a longitudinal tongue engageable with said slot whereby the tee is adjustably held in erected position with its side portions in downwardly diverging relation. 75 80 85

2. A golf tee comprising a strip of bendable material having spaced transverse scores to facilitate folding along predetermined lines and providing a top portion, side portions, and a pair of base portions adapted when the strip is folded on the scoring lines to lie in overlapping relation, the top portion having a hole therein providing a seat for the ball. 90 95

3. A golf tee comprising a strip of cardboard having transverse scores facilitating folding along predetermined lines and com- 100

prising a central portion constituting a top member and having a hole therein providing a ball seat, intermediate portions constituting side members and end portions constituting base members adapted to be brought into overlapping relation and having interlocking parts whereby the device is supported in erected position.

4. A golf tee comprising a strip of cardboard having transverse scores facilitating folding along predetermined lines and comprising a central portion constituting a top member and having a hole therein providing a ball seat, intermediate portions constituting side members, and end portions constituting base members adapted to be brought into overlapping relation.

In witness whereof I have hereunto set my hand,

20 THOMAS W. PHILLIPS.
